UNITED STATES PATENT OFFICE.

WILLIAM BRUMBLE, OF BALTIMORE, MARYLAND.

CAR-CO尤LING.

SPECIFICATION forming part of Letters Patent No. 285,221, dated September 18, 1883.

Application filed August 11, 1883. (No model.)

To all whom it may concern:

Be it known that I, WILLIAM BRUMBLE, of Baltimore, in the State of Maryland, have invented a new and useful Improvement in Couplings for Railway-Cars, of which the following is a clear, full, and exact description, reference being had to the accompanying drawings, making a part of this specification, in which—

Figure 1 is a perspective view of a coupling device with my improvement attached. Fig. 2 is a plan view of the coupling device with the upper portion of the draw-head removed. Fig. 3 shows the lever drawn to one side in the car to be coupled. Fig. 4 is a view of the lever detached.

The object of my invention is to enable a party to raise or lower the coupling-link to suit the car to be coupled, and to pass the link into the draw-head without having to go between the cars; and it consists of the combination of devices herein explained and claimed.

To enable others skilled in the art to make and use my invention, I will proceed to describe the exact manner in which I have carried it out.

In the drawings, A represents the draw-head; B, the coupling-link; C, the coupling-pin, and D the lever for operating and adjusting the draw-head and link to the car to be attached. The draw-head, link, and pin are all of the ordinary and well-known construction.

It is well known that when it becomes necessary to couple one car to another the intermediate coupling-link already attached to and in place on one car has to be adjusted to the other car, so as to conduct the link into the draw-head of the car to be coupled; and to accomplish this purpose I have constructed the lever D, which I will now proceed to describe. The lever-arm a has its inner end bent back upon itself, as shown in Fig. 4, and the upper

and lower portions are bent near their centers in opposite directions to open a downward passage between them for the coupling-pin, as shown in Fig. 2. The lever-arm a' is connected to the arm a by means of a hook and eye, as shown in Figs. 1 and 3. The outer ends of the two arms are bent down at right angles, or nearly so, and may be weighted to hold the lever steadily in its normal position. These arms are loosely attached by staples or other suitable means, so as to allow the lever to be drawn to one side, as shown in Fig. 3. This may become necessary when two cars are approaching to be coupled, and the lever on the car carrying the coupling-link needs only to be used. It is evident that the drawing the lever to one side, so as to remove central portion from the draw-head, does not cause the lever to interfere with the operations of the car, as the arm of the lever passes beneath the car-frame and out of the way.

The operation of my device is as follows: The link being in position in one draw-head and the coupling-pin resting between the double or folded portion of the arm a, it is only necessary to raise the outer bent portion of either of the arms in order to raise the link and also the draw-head within any limit which may be allowed for adjustment.

Having thus explained my invention, what I claim as new, and desire to secure by Letters Patent, is—

In combination with the draw-head, link, and pin of a coupling device for railroad-cars, the lever D, constructed as described, and consisting of the arm a, with its folded or doubled portion, and the arm a', attached thereto, substantially as herein described.

WILLIAM BRUMBLE
